UNITED STATES PATENT OFFICE.

HENRY EASTWOOD, OF PATERSON, NEW JERSEY.

LOOM.

SPECIFICATION forming part of Letters Patent No. 377,425, dated February 7, 1888.

Application filed March 12, 1887. Serial No. 230,602. (No model.)

To all whom it may concern:

Be it known that I, HENRY EASTWOOD, a citizen of the United States, residing at Paterson, Passaic county, State of New Jersey, have 5 invented a new and useful Improvement in Looms, of which the following is a specification, reference being had to the accompanying drawings, forming a part thereof.

Hitherto when two pieces of fabric have 10 been woven in the same operation in one loom—that is, with a fly-shuttle—usually the outer edges only of such two pieces of fabric have been finished or selvaged, while a narrow unwoven space between the two fabrics 15 has been left. The two pieces of fabric so woven, and afterward separated by cutting, have one raw or unfinished edge each, which must be finished by hand at a considerable outlay. It has been proposed to weave two dis- 20 tinct webs of fabric side by side in one loom with a perfect selvage on both sides through the use of fly-shuttles.

The object of my present invention is to 25 provide improved means by which, as in the last-mentioned method with fly-shuttles, any practical number of pieces of fabric can be woven in the loom, with both edges finished or selvaged in the same operation.

With this end in view my invention con- 30 sists in certain features of construction and combination of parts, hereinafter fully described, and pointed out in the claim.

Figure 1 of the drawings shows in elevation the front of an ordinary loom having my in- 35 vention applied thereto. Fig. 2 shows one end of the loom in elevation, and Fig. 3 shows in elevation the opposite end of the loom.

A represents an ordinary loom, having the usual supporting-frame, A', driving-shaft a, 40 crank-arms a'', pitman a', cam-shaft F', tappets F'', tappet-levers F' F'', cloth-beam C', ratchet and pawl C'', and gearing C' between the ratchet and cloth-beam, warp-beam C', lay C, and lay-swords P. The lay is shown as 45 having a number of the usual reed-frames, M, shuttle-boxes, N, and guards, K, and a single guard-supporting rod, L, applied thereto. The general loom, which is constructed as is usual, need not, it is thought, be further de- 50 scribed herein.

In a suitable position on the lay-swords P

of the loom A, I arrange and secure by bolts a transverse beam, B, which vibrates with the lay C and swords P, to which latter it is fastened, carries picking-sticks D 55 D' D'' D''' and levers E E'. These levers E E', which, like the picking-sticks, are secured to the beam B by pivot-bolts r', have integral with them inwardly-projecting arms G G', which arms connect with tappet-levers F'' F' 60 by means of connecting links or rods F F'. The picking-sticks D D' D'' D''' and levers E E' are connected together by means of straps J J' J'' and plates H H' H'' H''' and bolts H''. The picking-sticks and levers are connected 65 with the straps and plates by pivot-bolts H'', as shown, while the picking-sticks D D''' are provided with retracting-springs H'', one end of each of which springs is fastened to the beam B.

The driving-shaft a is put in motion in the usual way, and by means of crank-arms a'', pitman a', and gears a'' a''' vibrates the lay C and rotates the shaft F' and tappets thereon, which tappets in turn give the usual alternate 75 up-and-down motion to the heddles to form the sheds. The lay, by means of cord C', im- parts an up-and-down movement to the lever C'', which by means of pawl and ratchet C''' actuates the gearing between the ratchet-wheel 80 and cloth-beam, which turns the cloth-beam C''. The warps having been taken through the loom and the loom put in motion in the manner stated, the operation is as follows: Lever F'' is depressed by the action of the correspond- 85 ing cam, F'', which by means of link F draws down arm G of the lever E, throwing said lever outward, the lever taking with it in the same direction, through the connections stated, picking-sticks D D' D'' D''', which action of the 90 picking-sticks throws their respective shuttles through the sheds 1 2 3 into the boxes N on the left-hand side of the said sheds or web- spaces, (seen in Fig. 1,) the stick D, having been idle in the action. The lever F'', having 95 been raised in the last action of lever F'' through the connections, is next depressed by the cam's action thereon, and by means of link F'' draws down arm G' of lever E', throwing said lever outward, and through the connec- 100 tions stated throws picking-sticks D'' D''' D' in the same direction, which throws the shut-

ties back through their respective sheds 3 2 1 into the opposite shuttle-boxes N, to be returned by the action of lever E in the manner before stated. Thus the shuttles are thrown 5 alternately back and forth through the sheds while the weaving is continued. The fabrics are wound on the cloth-beam in the usual way, while springs H⁶ alternately draw and hold to their farthest outward position the picking- 10 sticks D D³. The guards K K' K² K³ serve to guide and limit the movement of the picker-sticks. Three sheds or spaces are shown. More may be added and more picker-sticks operated at the same time, if desired. 15 Having described my invention, I claim and desire to secure by Letters Patent—

The combination, with the levers E E' and picking-sticks D D' D² D³, straps J J' J², plates H H' H² H³, and bolts H⁴ H⁵, of beam B, adapted to carry said connected levers and picking-sticks, springs H⁶, rods or links F F', adapted to operate levers E E', all as described, lay C, lay-swords P, shaft a, crank-arms a'', pitmen a', for vibrating the lay, cam-shaft F⁴ and tapes thereon, and levers F² F³. 20

HENRY EASTWOOD.
